US0D1054986S

(12) **United States Design Patent** (10) **Patent No.:** **US D1,054,986 S**
(45) **Date of Patent:** **** Dec. 24, 2024**

(54) **CAPACITOR**(71) Applicant: **AmRad Manufacturing, LLC**,
Universal City, TX (US)(72) Inventor: **Robert M. Stockman**, Palm Coast, FL
(US)(73) Assignee: **AmRad Manufacturing, LLC**,
Universal City, TX (US)

(57) **CLAIM**

The ornamental design for a capacitor, substantially as shown and described.

DESCRIPTION

FIG. 1 is a perspective view of a capacitor;
FIG. 2 is a front view thereof;
FIG. 3 is a back view thereof;
FIG. 4 is a right side view thereof;
FIG. 5 is a left side view thereof; and
FIG. 6 is a top view thereof; and
FIG. 7 is a bottom view thereof.
